A. E. JERRAM

WORK POSITIONING DEVICE

Filed Oct. 8, 1920

UNITED STATES PATENT OFFICE.

ARTHUR ERNEST JERRAM, OF LEICESTER, ENGLAND, ASSIGNOR TO UNITED SHOE MACHINERY CORPORATION, OF PATERSON, NEW JERSEY, A CORPORATION OF NEW JERSEY.

WORK-POSITIONING DEVICE.

Application filed October 8, 1920, Serial No. 415,630, and in Great Britain November 28, 1919.

This invention relates to improvements in fastening inserting machines. As shown in the accompanying drawings, the invention is embodied in a nailing machine of the general type shown in the United States patent to Louis Goddu, No. 490,624, granted January 24, 1893, and operable to form a seam, consisting of a line of metallic fastenings, in the work operated upon.

It is usual in the fastening inserting machines used for a number of the operations employed in the manufacture of boots and shoes to provide an edge gage of suitable form against which the work is held during the operation of the machine to insert a series of fastenings parallel to the edge of the portion of the shoe operated upon. Some parts of shoes, however, are of such form that as they are moved by the work feeding means, for example an awl, past the edge gage there is a tendency at times for the work to cramp between the awl and the edge gage or for the edge of the work to separate from the edge gage due to the fact that the movement of the feeding means is in a straight line while the edge of the work may be and usually is curved and at times on a comparatively short radius. This tendency at times produces an objectionable irregularity in the spacing of the awl-holes from the edge of the work and may even result in a nail missing an awl hole.

An object of the invention accordingly is to provide in such machines improved means for accurately positioning the work for each of a series of operations performed on the work, the positioning being accomplished by the machine with a minimum of effort and attention on the part of the operative and in a simple and effective manner. In the illustrated embodiment of the invention this is accomplished by permitting the work feeding member and the edge gage to have movement transversely of the line of feed of the work during the feeding movement but so controlling said movement that at critical instants in the operation of the machine, such as at the conclusion of each feeding movement, the feeding member and the edge gage are positively positioned so that

the operation following each feeding movement is correctly performed at the desired location.

With this object in view, the herein disclosed machine is provided with an awl arranged to pierce and feed the work and with an edge gage to control the position of the work, the awl and the edge gage being carried by a bracket mounted for floating movement in a direction transversely of the line of feed and lightly spring-pressed towards the operator. By reason of the carrying of the awl and the edge gage by this bracket the edge gage is positively moved in the direction of the feed with the awl. This bracket carries a cam roll arranged for engagement, at the conclusion of the feeding movement, with an opening in a stationary member. This opening has an enlarged mouth so that the cam roll will enter it, irrespective of the position of the awl and edge gage transversely of the line of feed, but is formed with a seat arranged definitely to position the cam roll transversely of the line of feed at the conclusion of the feeding movement. Thus the operative is not required to hold the work up to a fixed gage or indeed to exercise any very accurate control of the work but may position it anywhere within considerable limits. In inserting fastenings around a curve of comparatively short radius, for example around the toe of a shoe, it is only necessary for the operator to keep the edge of the work within the range of the transverse movement of the edge gage. Moreover, any tendency to cramp or jam in passing around a curve of short radius, with the consequent danger of variation of spacing of the awl hole from the edge of the work and of the nail not being inserted in the awl hole, is eliminated, for during the feeding movement the gage moves with the awl and there is no relative movement of the gage and the work; while during the return movement the awl is free from the work so that there can be no cramping or jamming.

While in the accompanying drawings and specification the invention is disclosed as embodied in a nailing machine, it is to be dis-

tinctly understood that this is primarily for purposes of illustration and that the invention is, in many of its aspects, in no way limited thereto.

5 With the above and other objects and features in view, the invention will now be described with reference to the accompanying drawings and pointed out in the subjoined claims.

10 Fig. 1 of the drawings is a front elevation of the head of a loose nailing machine having work controlling mechanism in accordance with the present invention embodied therein;

15 Fig. 2 is a plan view of the work controlling means, certain parts of the machine being shown in cross section.

In the drawings, the invention is illustrated as applied to a nailing machine of the 20 type shown in said Letters Patent of the United States No. 490,624, provided with a swinging head 6 having a suitably operated driver 8 and an awl 10 operated in timed relation to said driver to penetrate and feed 25 the work to fastening inserting position and thereafter to be withdrawn for the insertion of a fastening. The fastenings may be fed through the usual raceway 11 into position to be inserted by the driver 8 30 through the usual throat 12 into the work. Any suitable form of separator 13 may be used to control the feed of the fastenings from the raceway to the throat in accordance with the usual practice.

35 The awl 10 is mounted upon the lower end of an awl bar 14 pivoted at its upper end at 16 to a shaft 18 mounted for oscillating movement in the lever 20. Relative endwise movement of the shaft 18 with respect 40 to the lever 20 is prevented, for instance by suitable collars or shoulders 22, 24 with which the shaft 18 is provided adjacent to the ends of lever 20. Lever 20 is rocked upon its fulcrum 26 carried by the swinging 45 head 6 to reciprocate the awl bar 14 to cause the awl to penetrate and be withdrawn from the work at appropriate intervals during the operation of the machine to pierce the work 50 for the insertion of the fastenings. The swinging head 6 is oscillated in the manner set forth in said Letters Patent to cause the awl 10 to feed the work step-by-step through the machine.

55 The connection of the awl bar 14 to lever 20 is such as to permit movement of the awl laterally of and approximately at right angles to the line of feed during the work feeding movement thereof.

60 Pivoted at 28 to the swinging head 6 of the machine is a bracket or lever 30 provided with a slideway 32 to receive for vertical sliding movement a block 34, said block being provided with a spherical bearing portion 36 to receive a spherical portion 38 65 carried by the awl bar 14. Thus it will be

seen that the bracket 30 may rock through a small angle about its pivot 28 in such manner as to move the awl transversely of the line of feed of the work without interfering with either the work feeding or work penetrating movement of the awl.

Rigidly attached to the bracket 30, as by screws 40, is an arm 42 having mounted therein, as by a screw and slot connection 44, an edge gage 46. Carried near the extremity of arm 42, is a cam roll 48 preferably adjustably connected to the arm 42, as by an adjustable eccentric 43. It should be here noted that the edge gage partakes of the work feeding movement of the awl since 70 both the awl and edge gage are carried by the bracket 30 which is mounted upon the swinging head 6 of the machine. Thus the awl and edge gage are at all times opposite one another when considered with respect to 75 the direction of the line of feed though they are mounted for floating movement together transversely of the line of feed during the work feeding movement in accordance with the contour of the work operated upon. 80 This movement of the awl and edge gage transversely of the line of feed is independent of the length of each feeding movement of the awl and is in no way detrimental to the proper positioning of the fastenings provided only that precautions are taken to ensure the correct relation of the edge gage and awl to the line of feed at the conclusion 85 of each feeding movement. To ensure this latter, a cam slot 50 is provided upon a relatively stationary part of the machine for engagement with the cam roll 48 correctly to position the edge gage and awl at the conclusion of each feeding movement. This 90 cam slot is formed with an entrance substantially wider than the diameter of the cam roll 48 so as to permit movement of the cam roll 48 transversely of the slot during the feeding movement and is provided at its terminal portion with a semi-cylindrical seat 52 of a diameter equal to the diameter of the cam roll 48 positively to position the cam roll and accordingly also positively to position the edge gage and the awl at the conclusion of each feeding movement. 95 Preferably cam slot 50 is formed in a plate 54 adjustably connected as by a screw and slot connection 56 with a plate 58 adjustably carried by a relatively stationary part of the machine and provided with a parallel sided slot 60 which may be moved into alignment with slot 50 to restrain the edge gage from movement at an angle to the line of feed in case the work operated upon is such that it is not desired to utilize 100 the work controlling means herein described.

A spring 62 is attached at one end to arm 42 and is anchored at its other end to the swinging head 6 or to another suitable part of the machine and tends to swing 105

the arm 42 and bracket 11 in a counter-clockwise direction, as viewed in Fig. 2, to hold the cam roll 48 in contact with the forward surface of cam slot 50.

5 In the operation of the machine, the work is pressed by the operative against the edge gage 46. During the feeding movement of the awl the cam roll 48 moves in the cam slot 50, at the conclusion of the feeding movement bringing up in the terminal portion 52 thereof to locate the work in correct nail driving position. If, during the return movement of the awl the edge gage meets a curve on the work extending toward the rear of the machine, the edge gage, and with it the awl, will be moved by the engagement of the edge gage with the work towards the rear of the machine about the pivot 28 of bracket 30 against the tension of spring 62 and during the next feeding movement the rear face of the cam slot 50 will guide the cam roll 48 to the terminal portion 52 of the cam slot correctly to position the work to receive a fastening. Should the curve on the work extend toward the front of the machine the edge gage, during the return movement of the awl, will move toward the front of the machine by virtue of the action of spring 62 which will hold the edge gage in engagement with the work and upon the next feeding movement of the awl the front surface of the cam slot 50 will be engaged by the roll 48 to ensure the movement of the work into correct nail-receiving position. In brief, whatever the position of the work with relation to the desired line of feed during the feeding movement, it will be brought into correct relation thereto at the conclusion of each feeding movement by the seating of cam roll 48 in the seat 52 provided at the terminus of slot 50.

Having described my invention, what I claim as new and desire to secure by Letters Patent of the United States is:

1. A fastening inserting machine having a reciprocating nail driver, a co-operating reciprocating work-feeding awl, and a gage arranged for engagement with the edge of the work and mounted to move relatively to its support in the machine to contact with the edge of the work in different positions thereof in the plane of the work and correspondingly to determine thereby the point in the work and relatively to the machine at which the awl acts on the work, together with means invariably moving the awl from its position of penetration into line with the driving path of the driver.

2. A machine of the class described having a work feeding member free to move transversely of the line of feed during a part of its work feeding movement, and a cam arranged to guide the feeding member from any position which it may assume during

its work feeding movement to a predetermined position.

3. A machine according to claim 2 provided with an additional cam having an operative and an inoperative position and adapted when in operative position to guide the work in a fixed path during the feed movement thereof.

4. A machine for inserting fastenings having, in combination, an awl arranged to feed the work, and an edge gage, the edge gage and the awl being movable in unison transversely of the direction of feed, and means for moving the edge gage into a predetermined position at the conclusion of each feeding movement.

5. A machine for inserting fastenings having, in combination, an awl arranged to feed the work, and an edge gage, the edge gage and the awl being yieldingly mounted for movement in unison transversely of the direction of feed, and positive means for moving the edge gage into a predetermined position at the conclusion of each feeding movement.

6. A machine for operating upon shoes having, in combination, an awl arranged for work penetrating and feeding movement, and an edge gage in co-operative relation to said awl constructed and arranged for floating movement transversely of the work during the work feeding movement.

7. A machine for operating upon shoes having, in combination, means for feeding the work, an edge gage for the work, normally supported for movement transversely of the line of feed of the work through the machine and separate from the feeding means, and means for ensuring a uniform relation of the gage to the line of feed at critical instants in the several cycles of operation of the machine.

8. A machine for forming a seam thereby to connect shoe parts having, in combination, means for feeding the work through the machine capable of movement transversely of the direction of the seam, a gage constructed and arranged for movement with said feeding means transversely of the direction of the seam, and means positively to position said feeding means and gage with respect to the line of the seam at critical instants in the operation of the machine.

9. A machine for operating upon shoes having, in combination, a work feeding member and an edge gage, said feeding member and edge gage being arranged for movement transversely of the line of feed, and means for positively positioning the feeding member and the edge gage with respect to the line of feed at critical instants in the operation of the machine.

10. A machine for operating upon shoes having, in combination, a step-by-step operated work feeding member and an edge

- gage, said feeding member and edge gage being arranged for movement transversely of the line of feed, and means for positively positioning the feeding member and edge gage with respect to the line of feed at the conclusion of each feeding movement.
11. A machine for operating upon shoes having intermittently operated feeding means and an edge gage to position the work with respect to said feeding means movable in the direction of feed with said feeding means and having capability of movement in a direction, transversely of the line of feed, and means for ensuring the correct position of the edge gage at the completion of each feeding movement.
12. A machine for operating upon shoes having step-by-step operated feeding means and an edge gage to position the work with respect to said feeding means movable in the direction of feed with said feeding means, said edge gage and said feeding means being arranged to have capability of movement transversely of the line of feed, and means for ensuring the correct position of the feeding means and edge gage at the completion of each feeding movement.
13. A machine for inserting fastenings in shoes having, in combination, an awl, means to move said awl in a direction to feed the shoe part operated upon through the machine, an edge gage opposite said awl, said awl and edge gage having capability of movement transversely of the line of feed, and means for ensuring the correct relation of the awl and edge gage to the line of feed at the conclusion of each feeding movement.
14. A machine for forming a seam thereby to connect shoe parts having, in combination, an awl capable of movement transversely of the line of feed, means for giving said awl alternating work penetrating and work feeding movements, an edge gage constructed and arranged for movement with said awl transversely of the line of feed, and means positively to position said awl and edge gage with respect to the line of feed at the conclusion of each work feeding movement.
15. A machine for inserting fastenings in shoes having, in combination, a movable bracket, an awl carried by said bracket, means for giving said awl a feeding movement to feed the work through the machine, an edge gage carried by said bracket and arranged for movement with said bracket and said awl transversely of the line of feed of the work, and means positively to position said awl and edge gage with respect to the line of feed at the conclusion of each feeding movement.
16. A machine for inserting fastenings in shoes having, in combination, a pivoted bracket, an awl carried by said bracket, means for giving said awl a feeding movement to feed the work through the machine, an edge gage carried by said bracket and arranged for movement with said bracket and said awl transversely of the line of feed of the work, and means for ensuring the correct relation of said awl and edge gage to the line of feed at the conclusion of each feeding movement.
17. A machine for inserting fastenings in shoes having, in combination, a movable bracket, work feeding means carried by said bracket, an edge gage carried by said bracket and arranged for movement with said bracket and said awl transversely of the line of feed of the work, and a pair of co-operating elements carried by a relatively stationary part of the machine and by said movable bracket respectively for positively positioning the work feeding means and the edge gage with respect to the line of feed of the work at critical instants in the operation of the machine.
18. A machine for inserting fastenings in shoes having, in combination, a movable bracket, an awl carried by said bracket and arranged for universal movement, means to give said awl work penetrating and work feeding movements, an edge gage carried by said bracket and arranged for movement with said bracket and said awl transversely of the line of feed of the work, and a pair of co-operating elements carried by a relatively stationary part of the machine and by said movable bracket respectively for positively positioning the awl and the edge gage with respect to the line of feed of the work at the conclusion of each feeding movement.
19. A machine for inserting fastenings in shoes having, in combination, a movable bracket, an awl carried by said bracket and arranged for alternate work penetrating and work feeding movements, an edge gage carried by said bracket and arranged for movement with said bracket and said awl at an angle to the line of feed, a cam carried by a relatively stationary part of the machine and having a surface arranged for contact with an engaging member carried by said bracket positively to position said edge gage and awl with respect to the line of feed at the conclusion of each feeding movement, and means tending to move said engaging member into contact with a surface of said cam.
20. A machine for inserting fastenings in shoes having, in combination, a movable bracket, an awl carried by said bracket and arranged for alternate work penetrating and work feeding movements, an edge gage carried by said bracket and arranged for movement with said bracket and said awl transversely of the line of feed, a cam carried by a relatively stationary part of the machine and having a portion of its surface

arranged for contact with a cam roll carried by said bracket positively to position said edge gage and awl with respect to the line of feed at the conclusion of each feeding movement, and a spring tending to move said cam roll into contact with the surface of said cam.

21. A machine for inserting metallic fastenings in shoes having, in combination, an awl, means for operating the awl to cause it to penetrate, to feed and then to withdraw from the stock, means operated in timed relation to the awl to insert a fastening in the hole made by the awl after the withdrawal of the latter, and an edge gage arranged in co-operative relation to the awl and mounted for movement in the direction of feed with the awl, said edge gage and awl having capability of movement transversely of the line of feed and means positively to position the awl and edge gage with respect to the line of feed at the conclusion of each feeding movement.

22. A machine for inserting metallic fastenings in shoes having, in combination, a driver, an awl, means for operating said awl in timed relation to the driver for piercing the work and feeding the work through the machine, and an edge gage constructed and arranged for floating movement transversely of the work during the work feeding movement of the awl.

23. A machine for inserting metallic fastenings in shoes having, in combination, an awl, means for operating the awl to cause it to penetrate, to feed, and then to withdraw from the work, a driver operated in timed relation to the awl to insert a nail in the hole made by the awl after the withdrawal of the latter, and an edge gage opposite the awl and arranged for movement in the direction of feed with the awl, said edge gage and awl having capability of movement transversely of the line of feed and being provided with means to ensure their correct relation to the line of feed at the conclusion of each feeding movement.

24. A machine for inserting fastenings having, in combination, an awl and a driver arranged for relative movement in a direction transversely of the work, means for operating the awl in timed relation to the driver to pierce and feed the work, and an edge gage arranged for movement parallel

to the movement of the awl during the work feeding movement of the awl.

25. A fastening inserting machine having a swinging head, an awl carried by said head arranged to pierce and feed the work, and an edge gage to control the presentation of the work to the machine, the awl and the edge gage being mounted for movement transversely of the direction of swing of the swinging head.

26. A fastening inserting machine having, in combination, work feeding means, and an edge gage separate therefrom, the edge gage and the work feeding means being arranged for movement transversely of the direction of feed.

27. A machine for operating upon shoes having, in combination, an awl arranged for work penetrating and feeding movement, an edge gage located to engage a work-piece fed by said awl and constructed and arranged for movement transversely of the path of feed during the work feeding movement, and means for positively positioning said edge gage transversely of the line of feed at the conclusion of the work feeding movement of the awl.

28. A machine for operating upon shoes having, in combination, a work feeding tool arranged to engage and feed a work-piece, means for giving said feeding tool a work feeding movement, and an edge gage located to engage the work-piece fed by said feeding tool and constructed and arranged for floating movement transversely of the line of feed during a portion of the work feeding movement.

29. A machine for inserting metallic fastenings in shoes having, in combination, a driver, an awl, means for operating said awl in timed relation to the driver to cause the awl to pierce the work and feed the work through the machine, an edge gage constructed and arranged for movement transversely of the work during a portion of the work feeding movement of the awl, and means for positively positioning said edge gage in a direction transverse of the line of feed at the conclusion of the work feeding movement.

In testimony whereof I have signed my name to this specification.

ARTHUR ERNEST JERRAM.
